(57) **CLAIM**

The ornamental design for a massage device as shown and described.

DESCRIPTION

FIG. 1 is a perspective view of a massage device showing my new design;

FIG. 2 is top view of the design shown in FIG. 1;

FIG. 3 is a front view of the design shown in FIG. 1;

FIG. 4 is a left side view of the design shown in FIG. 1;

FIG. 5 is a right side view of the design shown in FIG. 1;

FIG. 6 is a rear view of the design shown in FIG. 1; and,

FIG. 7 is a bottom view of the design shown in FIG. 1.

The evenly-spaced broken lines in the Figures illustrate portions of the massage device that form no part of the claimed design. The dash-dot-dash lines illustrate an unclaimed boundary line that forms no part of the claimed design.
